UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

AUTOMATIC TELEPHONE-EXCHANGE SYSTEM.

1,196,793.

Specification of Letters Patent. Patented Sept. 5, 1916.

Application filed June 8, 1915. Serial No. 32,824.

To all whom it may concern:

Be it known that I, ALBEN E. LUNDELL, a citizen of the United States, residing at New York, in the county of Bronx and State of New York, have invented certain new and useful Improvements in Automatic Telephone-Exchange Systems, of which the following is a full, clear, concise, and exact description.

10 This invention relates to telephone exchange systems employing machine switching, and more particularly to what are known as two-wire systems. In such systems it is customary to employ two slow acting relays for controlling a selector, one energized by impulses from the front contact of the stepping relay to maintain the release circuit open, and the other by impulses from the back contact of the stepping 15 relay, and thus, at the termination of the line circuit interruptions caused by the sender transmitting the digit of the called number involved in the operation of the selector in question, becoming deenergized 20 to operate an electromagnetic switch which brings about the necessary circuit changes to initiate the trunk hunting operation.

It is the object of this invention to provide an efficient selector circuit of this character wherein a single relay performs the functions which hitherto required the two slow relays above mentioned.

In accordance with this invention a relay, slow to attract its armatures, is employed, and is connected to both front and back contacts of the stepping relay. This relay is so constructed that it will not become sufficiently magnetized to attract its armatures as long as the sender is interrupting the line circuit, and consequently intermittently energizing the stepping relay, but will attract its armatures when the stepping relay closes its front or back contact for a relatively long interval.

45 The circuit of the release magnet of the selector leads by way of a front contact of the slowly operating relay and a back contact of the stepping relay. Thus, if when the slowly operating relay energizes, the stepping relay is deenergized, the selector will be released. This would be the case if the calling party hangs up his receiver, thus abandoning the call. If, on the contrary, the stepping relay is energized when the slowly operating relay energizes, an electro-

magnetic switch is operated to bring about the necessary changes to initiate the trunk hunting operation. This would be the normal case wherein the calling party's sender, in reaching its normal position after intermittently opening the line circuit, maintains the stepping relay energized.

50 The invention will be more readily understood when described with reference to the accompanying drawing, which shows diagrammatically only so much of a telephone system as is necessary for an understanding of the invention.

The calling line, whose substation is designated A, may be extended to the first selector 55 shown in any well-known manner, as for example, by one or more line finders. Assuming, therefore, that the calling line has, upon the removal of the receiver at substation A, been extended by a finder to the first 60 selector shown. The stepping relay 10 thereat is then energized over the following circuit: free pole of battery, left-hand winding of said relay, conductor 11, side switch arm 12 and its first contact, conductor 13, line conductor 16, through the telephone set at substation A, sender S, line conductor 17, conductor 18, side switch arm 22 and its 65 first contact, conductor 23, right-hand winding of relay 10 to ground. Relay 10, upon 70 energizing, closes at its armature and front contact a circuit for primary stepping magnet 25 as follows: free pole of battery, magnet 25, conductors 28, 29, contact spring 26 and its normal left contact, conductor 27, 75 armature and front contact of relay 10 to ground. The primary magnet 25 is energized and steps the selector shaft (not shown) one step in a primary direction, and transfers contact spring 26 from its normal 80 left contact into a neutral position between its right and left contacts. This is an idle step on the part of the selector switch shaft, and is not a part of its selecting operation. The relay 24, while in parallel with magnet 85 25, is so constructed as to attract its armatures only after a predetermined interval after the closure of its circuit, and does not become energized when relay 10 closes its front contact, since the spring 26 immediately thereafter opens its circuit.

100 The subscriber at substation A now operates the sender S a number of times, corresponding to the first digit of the wanted line. Each time the relay 10 is deenergized, 105

it sends an impulse to the primary magnet 25 over the following circuit: free pole of battery, stepping magnet 25, conductors 28, 29, 31, top armature and back contact of slowly operating relay 24, conductor 32, left armature and back contact of side switch magnet 33, conductor 34, spring 35, (closed on the first primary step to its right contact), conductor 36, armature and back contact of relay 10 to ground. Magnet 25 thereupon steps the selector brushes 37, 38, 39 in a primary direction into operative relation to the group of trunks corresponding to this digit of the wanted number. When the relay 10 remains energized, after the sender S has been restored, it closes its front contact for a sufficient length of time to energize the slowly operating relay 24 over the following circuit: free pole of battery, lower winding of relay 24, contact spring 40 (closed until the first secondary step of the selector shaft has been taken), conductor 41, contact spring 26 and its right contact (closed on the second primary step of the shaft), conductor 27, right armature and front contact of relay 10 to ground. The relay 24, by closing its lower armature and front contact, energizes the magnet 33, which is the escapement magnet of the side or steering switch, over the following circuit: free pole of battery, escapement magnet 33, conductor 42, side switch arm 43 and its first contact, conductor 44, lower armature and front contact of relay 24, conductor 45, right armature and back contact of release magnet 46, primary off-normal spring PON to ground.

The side switch magnet 33 is so arranged that it releases the side switch upon its energization only. In position 2 of the side switch its arm 50 closes a circuit for causing the secondary stepping magnet automatically to step the selector brushes 37, 38, 39 over the selected group of trunks in search of an idle trunk therein. This circuit is as follows: free pole of battery, stepping magnet 48, conductor 49, right armature and back contact of side switch magnet 33, side switch arm 50 and its second contact, interrupter 51 to ground.

50 Side switch arm 43, in position 2, connects the side switch magnet 33 in circuit with the test brush 39 of the selector to act as a test relay. Idle trunks are those upon whose test terminals 52 ground is present. When the test brush 39, therefore, encounters a test terminal 52, which is grounded at the back contact of the stepping relay 53 of an idle second selector, the side switch magnet 33 energizes, opening the stepping circuit of secondary magnet 48 at its right armature and back contact, and releasing the side switch to position 3. In position 3 of the side switch the calling line is connected through to the second selector thus seized, whose brushes 54, 55 only are shown. The

side switch arms 22', 12' belong to the side switch of this selector. Since this selector is identical with the first selector, only so much is shown as is necessary to comprehend the operation of the first selector. Continuing, therefore, when the side switch arms 22, 12 of the first selector move into position 3, the stepping relay 53 of the second selector is energized over the following circuit: free pole of battery, left winding of relay 53, side switch arm 12' of this selector and its first contact, contact 66, brush 38, conductor 68, brush 12 and its third contact, conductors 13, 16, telephone set at substation A, conductors 17, 18, brush 22 and its third contact, conductor 67, brush 37, terminal 65, side switch arm 22' of the second selector and its first contact, conductor 71, right winding of a stepping relay 53 to ground. This relay at its armature and back contact removes ground from the multiple test terminals 52, thus rendering the seized trunk unselectable by other selectors. In moving from positions 2 to 3, the side switch arms 22, 12 of the first selector cut off the stepping relay 10 from the line conductors 13, 18. The armature of said relay thereupon, at its back contact, closes the following circuit for relay 24: free pole of battery, upper winding of relay 24, conductor 32, left armature and back contact of magnet 33, conductor 34, spring 35 and its right contact, conductor 36, armature and back contact of relay 10 to ground. The relay 24 thereupon energizes, closing the following circuit for the magnet 33: free pole of battery, magnet 33, conductor 42, arm 43 and its third contact, conductor 44, lower armature and front contact of relay 24, conductor 45, right armature and back contact of release magnet 46, spring PON to ground. The first selector side switch thereupon moves into position 4, the arm 59 preparing the release circuit. It will be noted that since the side switch magnet cannot be moved out of position 3 until the relay 24 closes its front contact, and since this relay is slow to close such contact due to its construction, it follows that ground will be removed from conductor 62 by relay 53, (energized as arms 22, 12 move into position 3) before the arm 59 engages its fourth contact connected to said conductor 62. Thus there is no danger of premature release. The second selector is now operated in a manner similar to that already described, under control of the calling party's sender S, to pick out a connector, whose brushes 56, 57 only are shown, having access to the desired line, which connector is in turn operated by the subscriber in the well-known manner to connect with the wanted line, after which the line is tested and rung if idle, or the connector released and a busy signal given back to the calling party if busy.

Referring back to the setting of the first

selector, it will be observed that the relay 24 is provided with two windings. The circuit of the upper winding is controlled at the back contact of the line relay 10. The circuit of the lower winding is controlled at the front contact of the line relay 10. Thus, since this relay 24 is slow to attract its armatures, due to its construction, it will only respond when the armature of relay 10 rests 5 on its back or front contact for a predetermined interval of time long enough to energize the relay 24 by the corresponding winding. It follows from this that if, after the subscriber has removed his receiver and 10 before the selector switch has completed its operation and selected an idle trunk, he replaces it again, in other words, abandons the call, the selector is released over the following circuit, due to the energization of 15 said relay and the deenergized condition of the stepping relay 10: free pole of battery, release magnet 46, conductor 58, side switch arm 59 and its front contact, conductor 60, upper armature and front contact of relay 20 24, conductor 32, left armature and back contact of side switch magnet 33, conductor 34, contact spring 35 and its right contact (now closed), conductor 36, armature and 25 back contact of line relay 10, to ground. In 30 case the side switch of the selector is in position 2, that is, in case the selector switch is trunk hunting, the circuit of release magnet 46 is closed over the following circuit: free pole of battery, release magnet 46, conductor 35 58, side switch arm 59 and its second contact, secondary off-normal spring SON (closed on the first secondary step of the selector switch), upper armature and front contact of slow relay 24, left armature and 40 back contact of side switch magnet 33, conductor 34, contact spring 35, and its right contact (now closed), conductor 36, armature and back contact of line relay 10 to ground. The release magnet, by means of 45 its right armature and front contact, locks itself up in a circuit controlled at primary off-normal contact PON, which opens when the selector reaches its normal position, and opens the said locking circuit. Assuming, 50 however, the connection has been set up and the calling subscriber, upon the conclusion of the conversation, hangs up his receiver. This causes the release of the connector and second selector, the second selector, in reaching 55 its normal position, placing a ground upon test terminal 52 by the closure of spring 64 thereof (closed only in the normal position of the selector). This causes the release of the first selector by the closure 60 of the following circuit: free pole of battery, release magnet 46, conductor 58, side switch arm 59 and its fourth contact, conductor 62, test brush 39, test contact 52, conductor 63, contact spring 64, armature and 65 back contact of relay 53 to ground.

The spring 35 of the first selector closes to its left contact when the selector reaches its normal position, and grounds conductor 72 leading back to the finder or equivalent switch to release the same.

70

The relay 24 is so wound that the magnetic field set up therein by the closure of the circuit through the stepping relay armature and its front contact and the upper winding is opposite to that set up by the closure of the circuit through the said armature, its back contact and the lower winding, in order to avoid the possibility of false operation of the relay.

80

1. In a machine switching telephone exchange system, the combination with a selector, a stepping relay associated therewith, a sender for intermittently operating the same, a stepping magnet controlled by said stepping relay and a release magnet, of a slowly operating relay, a circuit therefor controlled at the front contact of said stepping relay, another circuit therefor controlled at the back contact of said stepping relay, and a circuit for said release magnet controlled at a front contact of said slowly operating relay and a back contact of said stepping relay.

2. In a machine switching telephone exchange system, the combination with a selector, a stepping relay associated therewith, a stepping magnet controlled thereby, a sender for intermittently operating said stepping relay, a steering switch, a control magnet therefor and a release magnet, of a slowly operating relay, a circuit therefor controlled at the front contact of said stepping relay, another circuit therefor controlled at the back contact of said stepping relay, a circuit for said release magnet controlled at a front contact of said slowly operating relay and a back contact of said stepping relay, and a circuit for said steering switch magnet controlled at a front contact 110 of said slowly operating relay.

3. In a machine switching telephone exchange system, the combination with a selector, a stepping relay therefor, a stepping magnet controlled thereby, a sender for intermittently operating said stepping relay, a steering switch, a control magnet therefor and a release circuit, of a double wound slowly operating relay, a circuit controlled at the front contact of said stepping relay 115 including one of said windings, another circuit controlled at the back contact of said stepping relay including the other winding, said slowly operating relay having a pair of armatures, one of which is adapted 120 when attracted to close the circuit of said steering switch control magnet, and the other being adapted when attracted to close one break in said release circuit, another break in this circuit being closed at the back con- 125

- 4.
- tact of the armature of said stepping relay.
4. In a machine switching telephone exchange system, the combination with a selector, a stepping relay associated therewith,
- 5 a sender for intermittently operating the same, a stepping magnet controlled by said stepping relay, and a release magnet, of a double wound slowly operating relay a circuit controlled at the front contact of said
- 10 stepping relay including one of said windings, another circuit controlled at the back contact of said relay including the other winding, the magnetic field set up in said relay by the closure of one of said circuits
- 15 being opposite to that set up by the closure of the other, and a circuit for said release magnet controlled at a front contact of said slowly operating relay and the back contact of said stepping relay.
5. In a machine switching telephone exchange system, the combination with a selector, a stepping relay associated therewith, a sender for intermittently operating the same, a stepping magnet controlled by said stepping relay and a release magnet, 25 of a slow relay controlled by said stepping relay and constructed and arranged to remain inoperative while said sender is operating, and to operate when the intermittent actuation of said stepping relay is discontinued, and a circuit for said release magnet controlled at a front contact of said slow relay and a back contact of said stepping relay.

In witnesss whereof, I hereunto subscribe 35 my name this 5th day of June A. D., 1915.

ALBEN E. LUNDELL.
